UNITED STATES PATENT OFFICE

133,534

DESIGN FOR A COMBINATION GRATER AND VEGETABLE SHAVER

Nathan K. Morris, Asbury Park, N. J.

Application January 6, 1942, Serial No. 105,040

Term of patent 7 years

To all whom it may concern:

Be it known that I, Nathan K. Morris, a citizen of the United States, residing at Asbury Park, county of Monmouth, and State of New Jersey, have invented a new, original, and ornamental Design for a Combination Grater and Vegetable Shaver, of which the following is a specification, reference being had to the accompanying drawings, forming a part thereof.

I claim:

The ornamental design for a combination grater and vegetable shaver, as shown.

NATHAN K. MORRIS.
